Primary Examiner — Clare Ann Gannon

(57) **CLAIM**

The ornamental design for an anti-mosquito curtain, as shown and described.

DESCRIPTION

FIG. 1 is a front view of the anti-mosquito curtain showing my new design;

FIG. 2 is another front view thereof;

FIG. 3 is another front view thereof; and,

FIG. 4 is a fragmentary enlargement view thereof of the area 4 shown in FIG. 1.

The broken lines shown in the drawings depict portions of the anti-mosquito curtain that form no part of the claimed design.
